UNITED STATES PATENT OFFICE.

FRANK McINTYRE, OF NEW YORK, N. Y., ASSIGNOR TO EAGLE PENCIL COMPANY, OF NEW YORK, N. Y.

PENCIL-TIP.

No. 813,106.

Specification of Letters Patent.

Patented Feb. 20, 1906.

Application filed December 16, 1905. Serial No. 292,022.

To all whom it may concern:

Be it known that I, FRANK McINTYRE, a citizen of the United States, residing at New York, borough of Bronx, State of New York, have invented a new and useful Improvement in Pencil-Tips, of which the following is a specification.

This invention relates to metallic pencil-tips designed to be mounted on lead-pencils and to hold erasive material.

It consists in a certain construction of the tip, which will first be described in connection with the accompanying drawings, forming part of this specification, and will then be more particularly pointed out in the claims.

In the drawings, Figure 1 is a perspective view of the tip and a portion of the pencil to which it is applied. Fig. 2 is a like view of the three tubular pieces or bands which make up the tip separated from one another. Fig. 3 is a longitudinal axial section of the tip and portion of the pencil on which it is mounted. Fig. 4 is a like sectional view of a modification.

The three parts of which the tip is composed, are lettered A B C, respectively, all made, preferably, of sheet metal, seamless and in tubular form. The piece A, which constitutes the upper exposed portion and main part of the tip and which I shall for distinction sake term the "barrel" contains the erasive material x in its upper end. Between its ends it has a circumferential knurl a , and from this knurl to its lower end it is of smooth exterior and slightly reduced in diameter as compared with the portion above the knurl, the reduction in diameter being to enable this portion b of the barrel to receive upon it the pieces B C, which have the same diameter practically as the upper portion of tube A.

The part B as represented in the drawings is a comparatively narrow seamless band. The part C, which I term for distinction sake the "thimble," is a ring formed with a circumferential knurl c . This ring is a retaining-ring, the band B being held between its knurl c and the knurl a on the barrel. When the tip is provided with more than one band B, as in Fig. 4, then a similar retaining-ring c' with such obvious modifications as called for by the change in location is interposed between adjoining bands.

In fitting the parts together the band or ring B is first slipped onto the portion b of the barrel A. Then the thimble C is fitted upon

the same portion b and pushed along the same until it brings up against the ring or band C, the latter being held between the knurls a and c , which constitute shoulders between which it is confined and kept in place. The tip as a whole is then fitted upon the end of a pencil P and is held thereon by the usual indentation or indentations i , (made by a suitable indenting-tool,) whereby not only are the thimble and barrel A united together, but the tip as a whole is made fast to the pencil.

A tip of this kind requires for its making a little more metal than the ordinary seamless one-piece tip. It is, however, readily and cheaply made, and the lessened cost of labor, particularly where the tip is to be provided with any great degree of ornamentation or with a band of color differing from the body of the tip, offsets the increase in expense of material.

By way of illustration the drawings represent a tip in which the part B is a plain band of red color, while the body of the tip on each side of the band is of yellow gold color, these colors being represented in Fig. 1 by their appropriate conventional hatchings. The band B can be most readily produced from a properly-colored tube of indefinite length, which can be expeditiously and cheaply divided up into bands of desired width.

Of course if two or more bands B are desired there would be a circumferentially-knurled spacing-ring between adjoining bands. Such a modification is shown in section in Fig. 4, in which there are two bands B, with a knurled spacing-ring between them. The construction in other respects is the same as already described in connection with the preceding figure.

Having described my invention and the manner in which the same is or may be carried into effect, I state in conclusion that I do not limit myself strictly to the structural details hereinbefore described in illustration of the invention, since manifestly the same can be considerably varied without departure from the spirit of the invention; but

What I claim herein as new, and desire to secure by Letters Patent, is—

1. In a metallic tip for lead-pencils, a barrel provided with a circumferential knurl, a knurled retaining-ring fitting upon the barrel, and a band also fitting upon the barrel and

held thereon between the knurl on the barrel and retaining-ring respectively, substantially as set forth.

2. A metallic tip for lead-pencils consisting of a barrel having at a point between its ends a circumferential knurl or shoulder, a knurled thimble fitted upon and secured to the forward portion of the barrel, and a ring or band also fitted upon the barrel, and held

between the knurls on the barrel and thimble respectively.

In testimony whereof I affix my signature in presence of two witnesses.

FRANK MCINTYRE.
